OSCILLATION GENERATION

Clarence W. Hansell, Port Jefferson, N. Y., assignor to Radio Corporation of America, a corporation of Delaware

Application July 14, 1930, Serial No. 467,831

19 Claims. (Cl. 250—36)

This invention has as its main object the provision of new and useful methods of and means for the production of electrical alternating oscillations. Broadly, it is an object of this invention to produce an electronic discharge or arc and, by producing relative motion between the discharge and a conductor, to induce potentials in the conductor by the action of the fields about the arc or discharge.

More specifically, it is an object of this invention to provide an arc and to provide for the rotation of the same by subjecting it to a magnetic field. Consequently by having one or more conductors in the path of the fields associated with the arc, electrical oscillations will be set up in the conductors.

Still a further object of this invention is to produce oscillations by shock exciting a tuned circuit with a traveling or rotating arc.

Still another object of this invention is to provide for the generation of polyphase currents with a rotating arc.

Another object of the present invention is to provide for the modulation and transmission of the oscillations produced in the manner hereinbefore outlined.

Referring to the accompanying drawing which is only illustrative of the present invention,

Figures 1 and 2 are right angled views, partly in section, of apparatus for producing a rotating electronic discharge in the form of an arc, the arc inducing currents in a nearby conductor,

Figure 3 discloses apparatus for utilizing a moving arc to shock excite a tuned circuit,

Figure 4 is a preferred arrangement of electrodes for shock exciting a tuned circuit,

Figure 5 is a modification of Figure 3 for shock exciting a tuned circuit,

Figure 6 indicates apparatus for modulating oscillations produced in accordance with the present invention, and

Figure 7 indicates, diagrammatically apparatus for obtaining, according to the present invention, polyphase currents.

Turning to Figure 1, by the application of a suitable potential to leads 2, an arc may be set up between an inner circular electrode 4 and an outer annular electrode 6, which electrodes together with conductors 8 are mounted within an hermetically sealed container filled with a suitable gas. For the sake of simplicity, the container or envelope has been shown by dotted lines. The container should contain a gas to start an arc, and the gas should be rarified in order to 55 reduce windage. By means of a solenoid 10,

preferably placed outside of the container, a magnetic field may be set up in a direction traversing the longitudinal axis of arc or electronic discharge 12.

Since the arc represents a current, application 5 of a magnetic field in the direction shown will cause it to rotate between the inner electrode 4 and the outer electrode 6 which may be supported, as shown in Figure 2, by means of supports 14 and annular insulator 16. Rotation of the arc past 10 the pick-up wires 8, joined at their outer extremities as shown by the single conductors 16, will induce potentials therein at a frequency determined by the pressure of the gas, the strength of the field, and the potential applied to the 15 leads 2.

The oscillations generated may be radiated from the conductors 16 or they may be fed into a land line or the like for transmission. Modulation may be accomplished by the application of 20 amplified complex currents through a transformer 20 to the field coils 10, and/or by application of keyed modulating alternating energy through a transformer 22 to the electrodes. In the event that both modulations are to be simultaneously 25 transmitted, the frequency of source 24 should be chosen above the audible range of frequencies, or, beyond the range of frequencies supplied by transformer 20.

The output of the oscillator modulated as described will be frequency modulated energy. In order to obtain, if desired, amplitude modulated energy, the arrangement shown in Figure 6 may be resorted to wherein the oscillator has been diagrammatically indicated by circle 26. The output of the oscillator is fed serially through a resistance in the form of the internal resistance of a thermionic tube 28 varied according to modulation potentials applied to the control electrode 30 thereof through a transformer 32. Accordingly, oscillations of varying amplitude are fed, through a blocking condenser 33 and lead 34, to an amplifier 36 and then, if desired, amplified and transmitted. If found desirable, in addition, a frequency multiplier 38 and a further amplifier 40 may be provided for radiation or transmission over a suitable antenna 42. To improve action 45 of the device, a tuned circuit 100 may be connected as shown ahead of amplifier 36.

The rotating arc may also be utilized for generation of oscillations by shock exciting a tuned circuit. Thus, for example, in Figure 3, a tuned circuit 44 is connected to outer terminals or electrodes 46, 48 about the center circular electrode 50, through the supports 14 and conductors 51, 55

52. A solenoid for producing a magnetic field is shown diagrammatically by circle 10.

Only a single arc is formed in the arrangement shown in Figure 3 as well as in the arrangement shown in Figure 1, for the reason that once an arc is started, the current flowing between electrodes, confines itself to that point since, at the point of the arc, impedance between the electrodes is less than at any other point. Application of the magnetic field causes the arc to rotate and jump from one of the outer electrodes 48 to the other electrode 49. My suitable choice of gas pressure, field strength and electrode potentials, rotation of the arc can be made such that tuned circuit 44 is properly shock excited for oscillation generation therein.

The output of tuned circuit 44 may be coupled as shown to an antenna 54 or, the output of tuned circuit 44 may be amplified before any desired type of further transmission. For modulation, as before, either the electrode potentials or field strength may be varied. Or, as shown in connection with Figure 3, an electron discharge device may be placed in series with the leads 14 to tuned circuit 44 or, in series with the electrode supply leads 2.

To insure the alternate jumping of the arc from one of the outer electrodes to another, or, in other words, from one terminal of tuned circuit 44 to the other terminal, the outer electrodes may be shaped as shown in Figure 4 where the arrow indicates the direction of rotation of the arc. The electrodes may be circular and placed eccentrically about the inner electrode 60; or, they are shaped in a fashion that as the arc travels along one of the outer electrodes, it is lengthened. Consequently, by suitable dimensioning of the electrodes, the arc will be elongated as it is continuously rotated. Then, as it approaches the near point of the next electrode it will prefer to jump to the next electrode rather than continue on the elongated path. As already indicated, because of the gas present, an arc will be set up, and it will inherently limit itself to one point rather than produce a plurality of arcs, one between each outer and inner electrode.

It is not necessary that, as in connection with Figure 3, the frequency of the tuned circuit be the same as the rotational frequency of the arc. Thus, by disposing a plurality of electrodes 60, 62, 64, 66 about a central electrode 68, as shown in Figure 3, and connecting alternate electrodes together, a tuned circuit 70, may be tuned to a frequency equal to twice the rotative speed of the arc, and, motion of the arc from one electrode to another will properly excite the tuned circuit 70 for oscillation generation. The output of tuned circuit 70 may be amplified in amplifier 72 and radiated by any suitable radiating device 74. Modulation may be accomplished in any one of the ways described hereinbefore.

Turning to Figure 7, by placing a plurality of pick up wires 80, 82, 84 of a number corresponding to the number of phases desired, polyphase currents may be set up therein by a rotating arc produced by the apparatus described and diagrammatically indicated by circle 80. If desired, radiation may be made direct from the pick up wires 80, 82, 84 in which case a rotating beam of energy will be propagated through space.

I claim:

1. In an oscillation generation circuit comprising an envelope and a conductor in close proximity to said envelope, the method of producing electrical oscillations which includes producing

an arc discharge within said envelope and establishing relative motion between the discharge and the conductor whereby the field of the discharge induces potentials in the conductor.

2. In an oscillation generation circuit comprising an envelope and a conductor in close proximity thereto, the method of producing electrical oscillations which includes producing an arc discharge in said envelope, establishing relative motion between the discharge and said conductor whereby the magnetic field of the discharge induces potentials in the conductor, modulating the oscillations so produced by varying the magnetic field of the discharge and transmitting the modulated oscillations.

3. In an oscillation generation circuit comprising a gas filled envelope and a conductor near said envelope, the method of generating oscillations which includes producing an arc within said envelope, and rotating the arc past the conductor to induce oscillations therein, modulating the oscillations so produced by varying the rate of rotation of said arc, and transmitting the modulated oscillations.

4. In an oscillation generation circuit comprising an envelope and a conductor in proximity to said envelope, the method of producing oscillations which includes producing an arc discharge in said envelope, rotating the discharge past the conductor such that the magnetic field of the discharge induces high frequency potentials in the conductor.

5. In an oscillation generation circuit comprising an envelope and a conductor in proximity to and external of said envelope, the method of generating alternating electrical oscillations which includes producing a rotating arc discharge in said envelope in one direction, subjecting the discharge to a magnetic field to produce motion of the discharge past said conductor whereby there are induced alternating potential oscillations in said conductor.

6. In an oscillation generation circuit comprising an envelope and a conductor in proximity to said envelope, the method of generating oscillations which includes producing an arc in said envelope, applying a unidirectional magnetic field thereto in a direction such that the arc is rotated whereby the magnetic field of the rotating arc induces alternating potential oscillations in said conductor.

7. The method of generating high frequency oscillations in a tuned circuit which includes producing an arc, continuously rotating said arc in one direction only and shock exciting the circuit with said arc discharge.

8. The method of generating oscillatory currents in a tuned circuit which includes producing an arc, establishing continuous motion of said arc in only one direction, and alternately connecting said arc with opposite terminals of the tuned circuit as said arc moves in said one direction.

9. An oscillation generator comprising a sealed envelope containing within it a gas and a plurality of electrodes, means for producing an arc between two electrodes within said envelope, a circuit for utilizing the oscillations produced by said generator including a conductor, and means for substantially continuously rotating the arc in a single direction past said conductor for setting up electrical currents therein.

10. An oscillation generator comprising means for producing an arc, means for continuously rotating the arc, and a conductor in the path of the

magnetic field of the rotating arc whereby currents are electromagnetically induced therein.

11. An oscillation generator comprising means for producing an arc, means for establishing motion of said arc by subjecting the arc to a magnetic field, and a conductor in close proximity to the arc adapted to have potentials induced therein by the magnetic action of said arc.

12. In a signaling system, means for producing an arc, means for producing an electromagnetic field in a direction traversing the longitudinal axis of the arc whereby the arc is rotated, and means including a conductor in the path of the magnetic field of the rotating arc whereby currents are electromagnetically induced therein.

13. In a signaling system a circular electrode, another electrode about said circular electrode, means for applying a potential difference across said electrodes whereby an arc is formed, means for applying a magnetic field in a direction perpendicular to the axis of the arc whereby the arc is rotated, and a conductor in close proximity to said arc adapted to have electrical currents set up therein due to the rotation of the arc.

14. An oscillation generator comprising means including a pair of electrodes which are substantially concentric for producing an arc, a magnet coil arranged around said generator for continuously rotating the arc, and a conductor in the path of the magnetic field of the arc adapted to have potentials produced therein by the action of the arc.

15. In a signaling system, a gas filled envelope, a circular electrode within said envelope, another electrode substantially concentric with and surrounding at least partially said circular electrode, a source of potential external of said envelope and connected to both of said electrodes for producing an arc, a magnet coil surrounding said envelope for establishing a rotating motion of said arc, and utilization means responsive to motion of the arc, and utilization means responsive to motion of

said arc whereby alternating currents are produced therein.

16. A system as defined in claim 15 characterized in this, that said magnet coil is energized by a source of unidirectional potential which sets up a magnetic field in a direction traversing the longitudinal axis of said arc.

17. An oscillation generator system comprising a gas filled envelope, a circular electrode within said envelope, two comma shaped electrodes surrounding at least partially said circular electrode on opposite sides thereof, a source of potential external of said envelope and connected to said circular electrode and to said comma shaped electrodes for producing an arc between said circular electrode and said comma shaped electrodes, and means surrounding said envelope for establishing a rotating motion of said arc, and utilization means responsive to motion of said arc adapted to have alternating currents produced therein.

18. An oscillation generator comprising a pair of substantially concentric and coplanar electrodes, a source of potential connected between said pair of electrodes for producing an arc therebetween, a magnet coil arranged around said generator for continuously rotating the arc, and a conductor in the path of the arc adapted to have potentials produced therein by the action of the arc.

19. In a signaling system, a gas filled envelope, a circular electrode within said envelope, an arcuate-shaped electrode substantially concentric with and surrounding at least partially said circular electrode, a source of potential external of said envelope and connected to both of said electrodes for producing an arc, a magnet coil surrounding said envelope for establishing a rotating motion of said arc, and utilization means responsive to motion of said arc whereby alternating currents are produced therein.
